UNITED STATES PATENT OFFICE.

JOSEPH WISHART, OF NEW YORK, N. Y., ASSIGNOR TO HOBBS, BENTON & HEATH, A FIRM OR COPARTNERSHIP.

DESIGN FOR WALL-PAPER.

No. 38,692.

Specification for Design.

Patented July 16, 1907.

Application filed April 24, 1907. Serial No. 370,081. Term of patent 3½ years.

To all whom it may concern:

Be it known that I, JOSEPH WISHART, a subject of the King of England, and a resident of the borough of Brooklyn, in the city of New York, in the county and State of New York, have invented a new, original, and ornamental Design for Wall-Paper.

The new design for wall paper is shown in plan in the accompanying drawing.

I claim
The ornamental design for wall paper as shown.

JOSEPH WISHART.
